UNITED STATES PATENT OFFICE.

WALLACE E. MEYERS, OF NEW YORK, N. Y., ASSIGNOR TO LOUIS MEYERS & SON, INC.,
OF NEW YORK, N. Y., A CORPORATION OF NEW YORK.

DESIGN FOR A GLOVE OR THE LIKE.

Application filed May 18, 1926. Serial No. 17,762. Term of patent 7 years.

To all whom it may concern:

Be it known that I, WALLACE E. MEYERS, a citizen of the United States, residing in the city of New York, borough of Manhattan, in the county and State of New York, have invented a new, original, and ornamental Design for Glove or the Like, of which the following is a specification, reference being had to the accompanying drawings, forming part thereof.

The design consists of raised zigzag lines, with embroidery or the like of a contrasting color between the lines.

The raised zigzag lines are formed of the same material as that of the body of the glove.

I claim:

The ornamental design for a glove or the like, as shown and described.

WALLACE E. MEYERS.
